UNITED STATES PATENT OFFICE.

LOWE E. SIMPSON, OF COLLEGE HILL, OHIO.

HYDROPLANE-BOAT.

No. 909,468.

Specification of Letters Patent.

Patented Jan. 12, 1909.

Application filed January 14, 1907. Serial No. 352,198.

To all whom it may concern:

Be it known that I, LOWE E. SIMPSON, a citizen of the United States, residing at College Hill, in the county of Hamilton and State of Ohio, have invented certain new and useful Improvements in Hydroplane-Boats, of which the following is a specification.

It is the object of my invention to provide a hydroplane boat with a body adapted to support the boat by displacement when the same is at rest on the water and which body is adapted to rise with relation to the surface of the water for reducing displacement when the boat attains speed, this rising being accomplished through the medium of hydroplanes which, in the operation of the boat, preferably remain submerged, and remaining submerged, are unaffected by the surface motion or waves of the water, and it is the further object of my invention to provide a boat of the character mentioned with adjustments by which the hydroplanes are under instant control of the operator for either causing the boat to rise or fall throughout its length and width or at its bow or stern, or from side to side, so that the boat may be at all times kept on a level with the water irrespective of distribution of weight on the boat and so that the boat may be easily dirigible. The speed possible in my improved device is very great.

It is especially desirable with high speeds, or in rough weathers and choppy seas, or where undue and unexpected resistance is liable to be encountered at different parts of the boat from different directions, that the hydroplanes may be manipulated instantly to counteract or overcome the same, and I provide means for accomplishing this.

It is the further object of my invention to provide a hydroplane boat having hydroplanes and propeller continuously submerged during propulsion of the boat, in which the various adjustments and connections with the motive and dirigible parts may be made above water so that instant attention or repair may be given to any of those parts, and in accomplishing these objects, I prefer to pivot the hydroplane-frames on which the hydroplanes are mounted above the normal level of the water, to connect the propeller-shaft with the motive power above the normal level of the water, and to construct the propeller shaft in such manner that its propeller end may be raised

above the normal level of the water for attention to the propeller.

My invention consists in means employed for accomplishing these various objects, and the invention will be further understood from the following description and claims, and from the drawings, in which latter:

Figure 1 is a side elevation of my improved hydroplane boat. Fig. 2 is a plan view of the same. Fig. 3 is a front elevation of the same. Fig. 4 is a perspective view of the rudder controlling mechanism. Fig. 5 is a side elevation of the rudder and the connections of the propeller shaft at the forward end of the latter, partly in section on the line $x-x$ of Fig. 2. Fig. 6 is a perspective view of the swivel-support for the hydroplane controlling-shaft, partly broken away. Fig. 7 is a detail elevation, partly in section, showing the means of releasable attachment of the fuel-tank to the cross-bars; and, Fig. 8 is a similar view showing the means of releasably securing the motor and its pillow-block in place, and, Fig. 9 is a detail in section of the platform.

1 represents the body of the boat which normally, when the boat is at rest, rests upon the water and is supported thereon by displacement, as indicated by the dotted line a representing the normal surface of the water. I have shown the body as comprising the hollow tubes 2 2', preferably of metal and which may respectively have tapered ends 3 4 3' 4'. These metal tubes act as 90 buoyancy members for the boat. A suitable number of cross-bars are provided for connecting the tubes. Thus I have shown a front cross-bar 5, a rear cross-bar 6, which may be slightly higher than the front cross-bar, and intermediate cross-bars 7 8 9, which latter form the support for the platform 10.

The platform comprises boards laid on the respective cross-bars, bolts 11 passing through the boards and plates 12 under the same, nuts 13 screwing over the lower ends of the bolts. (See Fig. 9). The cross-bars are secured to the tubes by means of straps 15 passing about the under surfaces and sides of the tubes and connecting with stirrups 16 at their ends, the cross-blocks 17 of the stirrups being on top of the cross-bars, compression-blocks 18 resting upon the tubes, the cross-bars resting upon the compression-blocks and being rigidly held in place by 110 screwing up the nuts 19. The compression-blocks and stirrups are of such relative sizes

as to locate the cross-bars at the desired heights. Braces 20 are secured between the compression-blocks of the cross-bars 7 8 9 for steadyng the same.

5 For driving the boat, I provide a suitable motor, as see the motor 21, shown as a four cylinder internal combustion motor comprising the cylinders 21^a 21^b 21^c 21^d. The crank-shaft casing 22 of the motor is releasably secured to a pillow-block 23 by nuts and bolts 24. The pillow-block is releasably secured to the cross-bars 7 8 by caps 25 under said bars and secured to the pillow-blocks by bolts 26. (See Fig. 8).

10 15 27 is a tank containing the fuel for the motor, as gasolene, which is fed through the pipe 28. The tank is releasably secured to the cross-bars 8 9 by straps 29 passing about the tank to the sides of each of said cross-bars, the lower ends of the straps passing through plates 30 under the respective cross-bars, nuts 31 holding the parts in place. (See Fig. 7).

32 represents the crank-shaft of the motor 25 and 33 the fly-wheel thereof.

34 is the drive-shaft which connects with the motor-shaft 32 preferably by means of a clutch 35, so that the engine may be readily started without carrying the load of the propeller-shaft. The clutch is operated from a handle 36. The drive-shaft is journaled in a sleeve 37 of a bearing 38 on a stanchion 39 having fork-members 39^a 39^b, said fork-members at their lower ends having bearings 35 40 releasably secured to the cross-bar 5 by bolts 41.

44 is a propeller-shaft which at its forward end is journaled in a thrust-bearing 45. 46 is a propeller for the propeller-shaft. 40 This thrust-bearing is preferably pivoted about the cross-bar 5 by means of a cap-bearing 47. The propeller-shaft is also journaled in a bearing 48 at its stern-end. The bearing 48 has pivotal connection on a pin 45 49 with a hanger 50 comprising forks 50^a 50^b respectively secured to the cross-bar 6 by means of bearings 51, held in place by bolts 52. Removable bolts 53 form the connection between said forks and the bearings 51.

55 The forward end of the drive-shaft 34 is provided with a sprocket-wheel 55, and the forward end of the propeller-shaft is provided with a sprocket-wheel 56, about which sprocket-wheels the sprocket-chain 57 passes for conveying the power of the drive-shaft to the propeller-shaft.

60 In order to adjust the distance between the sprocket-wheels for loosening or tightening the sprocket-chain and also for permitting swinging of the propeller-shaft upon its pivoted front bearing, I provide means for lengthening or shortening the stanchion 39, the clutch 35 permitting sufficient swiveling between the drive-shaft 34

and the crank-shaft 32 for the purpose. I prefer to accomplish the adjustment of the stanchion by dividing the respective fork members 39^a 39^b thereof into divided end-members having turnbuckles 58 58' between them respectively, and for permitting this adjustment I articulate the respective ends of said fork-members with their bearings as indicated by the pivot-pins 59 59'.

70 If now it is desired to raise the propeller, the bolts 53 of the bearings 51 are released for releasing the hanger 50. This will permit the raising of the stern end of the propeller-shaft and permit the propeller to be inspected, repaired or replaced above the level of the water. If there should not be sufficient slack in the sprocket-chain to permit the sprocket-wheel on the propeller-shaft to swing sufficiently to bring the rear end of the propeller-shaft above water, the 80 sprocket-chain may be removed from the sprocket-wheels or the fork-members 39^a 39^b of the stanchion 39 shortened for permitting this movement or removal.

75 85 The hydroplane-frames are shown at 71 90 72 73. These comprise plane-members, *i. e.* hydroplanes proper, and upright members and, as will be seen, are pivoted above the normal level of the water and are also operated from points above the normal level of 95 the water by means of connections also above the normal level of the water, so that the parts are at all times accessible for inspection, repairing or other purposes. The hydroplane-frame 71 comprises a plane member 100 74, the uprights 75, the braces 76 and the connecting bars 77 78. The uprights have cap-bearings 79 79' connected thereto and journaled about the cross-bar 5 for forming a pivot for the front hydroplane-frame above the normal level of the water. The caps of the bearings are readily removed so that the hydroplane-frame may be raised out of the water for inspection, repair or other manipulation. It will be noted that 110 the uprights are of very narrow cross-section so as to afford as little resistance as possible to the water, that they flare outwardly toward their lower ends, and that their lower ends are bent for forming feet 115 80 80' riveted or otherwise secured to the plane-member 74.

120 The hydroplane-frame 72 comprises the plane-member 81, the uprights 82 82', the upper connecting bars 83 83' and the diagonal braces 84. The uprights flare outwardly toward their lower ends and at their lower ends are provided with feet 85 85' bolted or riveted to the plane-member. The hydroplane-frame 72 is provided with a 125 bracket 86. This bracket comprises side plates 87 88 secured to the uprights, the rear ends of which are provided with bearings 89 90 about the cross-bar 6. Collars 91 92 are releasably secured to the cross-bar 130

for laterally positioning the hydroplane-frame 72. The hydroplane-frame may be readily removed by slipping the same endwise off the cross-bar for raising the hydroplane out of the water. The side plate 88 extends diagonally as shown toward the side plate 87, the side plates at their forward end merging into a laterally extending arm 93.

10 The hydroplane-frame 73 is provided with a plane-member 95 and has uprights 96 96' connected by connecting bars 97 97' and braces 98. The uprights flare outwardly toward their lower ends and at their lower ends are provided with laterally extending feet 99 99' bolted or riveted to the plane-member. The hydroplane-frame 73 is provided with a bracket 100 comprising side plates 101 102 bolted or riveted to the uprights, the rear ends of said side plates being provided with bearings 103 104 about the cross-bar 6 for forming a pivot for the hydroplane-frame 73. Collars 105 106 are releasably secured to the cross-bar 6 for positioning the hydroplane-frame 73 laterally. The hydroplane-frame 73 may be readily removed by slipping the same endwise off the cross-bar 6. The side plate 102 has a diagonally extending portion which meets 30 the side-plate 101 for merging into a laterally extending arm 107.

The hydroplane-frames are connected with hydroplane controlling means in such manner that all the hydroplanes are under 35 instant and ready control for causing the boat to rise or fall on a level or for raising and lowering either the prow or the stern, and also for tilting the boat sidewardly so that all conditions of resistance to the boat 40 in any direction may be immediately met and counteracted. Thus 111 is a drum operated by a shaft 112 having a hand-wheel 113. The shaft 112 is rotatively and pivotally supported in such manner so that 45 it may be turned and swung upon its pivot in substantially all directions. The shaft is arranged to rotate in a swivel-sleeve 114, on which it is supported by a collar 115 secured to the shaft. The sleeve is supported 50 on trunnions 116 having bearing in a ring-member 117, which ring-member is provided with trunnions 118 having bearing in a casing 119. (See Fig. 6). The trunnions 116 and 118 having axes at substantially 55 right angles to each other. A flexible connection 121, which may take the form of a chain or cable, is suitably secured to the drum and passes therefrom to the upper end of the hydroplane-frame 71 to which it is 60 releasably secured at 122 to the connecting bar 77. For guiding the direction of the flexible connection 121 it is arranged to pass over pulleys 123 124. A flexible connection 125 is suitably secured to the drum 111 and 65 leads to and is connected with the arm 93

of bracket 86 of hydroplane-frame 72, and is guided thereto over pulleys 126 127, the pulley 126 being secured to one of the braces 20, and the pulley 127 being in the form of a pulley-block hung from a bracket 128 on 70 the adjacent cross-block 17. A flexible connection 131 is suitably secured to the drum and leads to and is connected with the arm 107 of bracket 100 of hydroplane-frame 73 and is guided thereto over pulleys 132 133. 75 The pulley 132 is secured under the platform 10 and the pulley 133 is in the form of a pulley-block hung from a bracket 134 on the adjacent cross-block 17, the bracket 134 being similar to the bracket 128.

80 135 shows the operator's seat, and when sitting or standing at the wheel 113 the operator may easily manipulate the boat.

141 is a rudder which is pivoted at its lower end on a pin 142 passing through 85 plane-member 74 and having an enlargement 143 under the latter. At its upper end this rudder has a rearwardly extending arm 144 which has a shank 145 journaled in a bearing 146 forming the upper pivot of the 90 rudder. This bearing 146 is secured to the connecting bar 78 by a bolt 147. A flexible connection 151 releasably connects with the swinging end of this rudder-arm and is guided to one side thereof, and a flexible 95 connection 152 is also releasably secured to the swinging end of this arm and is guided to the other side thereof. The flexible connection 151 is guided over pulley-blocks 153 154 and is secured to a steering-shaft 155 100 and wrapped about that shaft in one direction. The flexible connection 152 is guided over pulley-blocks 156 157 and is secured to and wrapped about the said steering-shaft, the wrapping of said flexible connection 152 about said shaft being in a direction opposite to the direction of wrapping of the flexible connection 151, so that when the said steering-shaft is turned in one direction, the flexible connection 151 will wrap 110 upon the same while the flexible connection 152 will unwrap from it, and vice versa. The pulley-blocks 153 156 are secured to the cross-bar 5 while the pulley-blocks 154 157 are secured to the cross-bar 9. Hand-wheels 115 158 158' are secured to said steering shaft, which is preferably journaled in bearings 159 under the seat 135, so that the rudder may be manipulated from either end of said seat. It will further be noted that the flexible connections to the rudder pass forwardly from the swinging end of the rudder-arm so that when the hydroplane-frame 71 is swung upon its pivot, undue strain upon the flexible connection or the arm may be 120 avoided, the said flexible connections first passing forward in a direction toward the pivot of said hydroplane-frame.

In operation, when the boat is at rest, or if but slight motion is imparted thereto, the 130

boat will be supported by displacement of its weight upon the water, the support being had through the tubes 2 2'. When the boat acquires speed and the hydroplanes are so set that the forward edges of the plane members will be above the rear edges thereof, the tendency will be to cause the boat to rise as upon an incline, and when proper inclination has been given the hydroplanes and the 10 propeller is speeded up, the tubes 2 2' will gradually emerge from the water and rise above the normal water level so that the support of the boat will be through the medium of the hydroplanes, which however remain 15 submerged, as see the dotted line b which represents the water-level under the last-named conditions. If it is desired to raise the prow of the boat, the shaft 112 may be swung upon its pivot for bringing the upper 20 end of said shaft forward, which will tip the upper end of the forward hydroplane-frame rearwardly and lower the arms of the rear hydroplane-frames. If on the other hand it is desired to raise the stern of the boat, the 25 upper end of the drum-shaft is tipped back. If it is desired to raise the right side of the boat the hand-wheel 113 is tipped toward that side which will raise the arm of the hydroplane-frame 72 and permit the arm of 30 the hydroplane-frames 73 to drop. If on the other hand it is desired to raise the left side of the boat, the hand-wheel 113 is shifted toward that side, which thereby raises the arm of the hydroplane-frame 73 and 35 permits the arm of the hydroplane-frame 72 to drop. The hand-wheel 113 may also be shifted toward any direction between the directions mentioned, and the boat will correspondingly rise in the direction toward 40 which the hand-wheel is shifted so that the manipulation of the hand-wheel is instinctive, the connections being so arranged that the hand-wheel is merely tipped in that direction indicated by that part of the boat 45 which it is desired to raise. If it is desired to raise the tubes out of the water, the hand-wheel is turned for winding all the flexible connections of the hydroplane-frames upon the drum and thereby adjusting all the plane 50 members to a greater angle to the horizontal. If desired, the hydroplanes may also be employed to cause quick stoppage of the boat as they may be swung on their pivots to such a great angle to the horizontal that so much 55 of their under flat sides will be presented forwardly and against the water as to arrest the progress of the boat.

It will be noted that the weights of the parts are distributed as equally as possible 60 upon the boat. By means of my device which permits the adjustment of the rise at either side or end of the boat, an equal distribution of the weight on the boat is readily compensated for by manipulation of the 65 hydroplane wheel. It will further be noted

that the various parts of the boat are reasonably connected with each other for constituting a collapsible or knock-down hydroplane boat.

Having thus fully described my invention 70 what I claim as new and desire to secure by Letters Patent is:

1. In a hydroplane boat, the combination with a normal supporting body, hydroplane-frames pivoted thereto above the normal 75 level of the water when said supporting body rests upon the water, said hydroplane-frames provided with submerged hydroplanes, a drum, and flexible connections between said drum and said respective hydroplane-frames whereby said hydroplanes are 80 simultaneously manipulated.

2. In a hydroplane boat, the combination of a normal supporting body, hydroplane-frames pivoted thereto, said hydroplane-frames comprising hydroplanes, a pivoted manipulating drum, and flexible connections 85 between said drum and hydroplane-frames whereby said hydroplane-frames may be simultaneously swung about their pivots by 90 revolving said drum and whereby said hydroplane-frames may be manipulated by swinging said drum upon its pivot.

3. In a hydroplane boat, the combination of a normal supporting body, a series of 95 hydroplane-frames pivoted thereto comprising a central hydroplane-frame at one end of said boat and side hydroplane-frames at the other end of said boat, a manipulating drum therefor, means for universally pivoting said drum, means for revolving said drum, flexible connections between said drum and said respective hydroplane-frames for simultaneously manipulating said hydroplane-frames by revolving said drum and 100 reversely swinging said side hydroplane-frames by pivotal movement of said drum, substantially as described.

4. In a hydroplane boat, the combination with a normal supporting body, a series of 110 hydroplane-frames pivoted thereto comprising a central hydroplane-frame at one end of said boat and side hydroplane-frames at the other end of said boat, a manipulating drum therefor, means for universally pivoting said drum, means for revolving said drum, flexible connections between said drum and said respective hydroplane-frames for simultaneously manipulating said hydroplane-frames by revolving said 115 drum and reversely swinging said side hydroplane-frames and the hydroplane-frames at the respective ends of said boat with relation to each other by the swinging movement of said drum, substantially as described.

5. In a hydroplane boat, the combination of a normal supporting body, hydroplane-frames pivoted thereto above the normal 120 level of the water when said body rests upon 125

said water, arms extending from said hydroplane-frames above the level of the water, a pivoted rotatable drum, flexible connections from said drum to said respective arms whereby said hydroplane-frames are manipulated by revolving said drum or swinging the same upon its pivot, said arms, drum and connections being above said normal level of the water, substantially as 10 described.

6. In a hydroplane boat, the combination of a normal supporting body of the boat, hydroplane-frames pivoted thereto, a propeller-shaft and propeller, the forward end 15 of said propeller-shaft being above the level of the water when said body normally rests upon said water and the stern end of said propeller-shaft being under water, a pivotal connection for the forward end of said propeller-shaft, a releasable stay for supporting the rear end of said propeller-shaft, whereby said propeller-shaft may be released and swung upon its pivot for exposure of the propeller above said water- 20 level, a motor on said boat, a drive shaft 25 connected thereto, driving means between

the forward end of said drive-shaft and the exposed end of said propeller-shaft, and adjusting means between the forward ends of said shafts.

30

7. In a hydroplane boat, the combination with a normal supporting body for the boat, of hydroplane-frames pivoted thereto above the normal level of the water when said boat rests upon the water, said hydroplane-frames, an arm for said rudder, an operating pivoted to one of said hydroplane-frames, a pivoted revolving drum, flexible connections between said drum and said hydroplane-frames, an arm for said rudder, an operating 35 shaft for the same, and flexible connections between said arm and operating shaft, substantially as and for the purpose specified.

35

In testimony whereof I have subscribed 40 my name hereto in the presence of two subscribing witnesses.

Corrections in Letters Patent No. 909,468.

It is hereby certified that in Letters Patent No. 909,468, granted January 12, 1909, upon the application of Lowe E. Simpson, of College Hill, Ohio, for an improvement in "Hydroplane-Boats," errors appear in the printed specification requiring correction, as follows: In line 36, page 5, the words "an arm for said rudder, an operating" should be stricken out and the following inserted instead; *comprising hydroplanes, a rudder;* and that the said Letters Patent should be read with these corrections therein that the same may conform to the record of the case in the Patent Office.

Signed and sealed this 9th day of February, A. D., 1909.

[SEAL.]

C. C. BILLINGS,
Acting Commissioner of Patents.

said water, arms extending from said hydroplane-frames above the level of the water, a pivoted rotatable drum, flexible connections from said drum to said respective arms whereby said hydroplane-frames are manipulated by revolving said drum or swinging the same upon its pivot, said arms, drum and connections being above said normal level of the water, substantially as 10 described.

6. In a hydroplane boat, the combination of a normal supporting body of the boat, hydroplane-frames pivoted thereto, a propeller-shaft and propeller, the forward end 15 of said propeller-shaft being above the level of the water when said body normally rests upon said water and the stern end of said propeller-shaft being under water, a pivotal connection for the forward end of said propeller-shaft, a releasable stay for supporting the rear end of said propeller-shaft, whereby said propeller-shaft may be released and swung upon its pivot for exposure of the propeller above said water- 20 level, a motor on said boat, a drive shaft 25 connected thereto, driving means between

the forward end of said drive-shaft and the exposed end of said propeller-shaft, and adjusting means between the forward ends of said shafts.

30

7. In a hydroplane boat, the combination with a normal supporting body for the boat, of hydroplane-frames pivoted thereto above the normal level of the water when said boat rests upon the water, said hydroplane-frames, an arm for said rudder, an operating pivoted to one of said hydroplane-frames, a pivoted revolving drum, flexible connections between said drum and said hydroplane-frames, an arm for said rudder, an operating 35 shaft for the same, and flexible connections between said arm and operating shaft, substantially as and for the purpose specified.

35

In testimony whereof I have subscribed 40 my name hereto in the presence of two subscribing witnesses.
